UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

REFRIGERATING UNIT OF FIRED CERAMIC MATERIAL

Application filed February 29, 1928. Serial No. 257,811.

This invention relates to refrigerating units of fired ceramic material, and has to do particularly with cooling units forming a part of automatic refrigerating systems and 5 formed in part of fired ceramic material.

It is the object of the present invention to provide a cooling unit for a water cooler, a domestic refrigerator, or in fact any type of refrigerating unit requiring the transmission 10 of heat units, and having its face or faces formed of fired ceramic material; and wherein in the transmission of heat between the contents of this fired ceramic cooling unit and the boiler or other expansion device is by 15 means of a fluid, and preferably a liquid.

In my copending application #248,314, filed January 21, 1928, I have disclosed the broad idea of embedding a metallic article adjacent to or within a fired ceramic unit by 20 positioning the metallic article within or adjacent the ceramic unit and filling up the space between the two by material plastically applied but allowed to set without firing.

The present invention differs materially from 25 the disclosure of said copending case, in that instead of positioning the cooling means, such as the boiler or expansion device by means of the plastically applied stone, said boiler or expansion device is positioned closely adjacent the wall or walls of the ceramic cooling 30 unit, preferably by the formation of the fired ceramic unit itself, and the heat transmission between the cooling medium and the contents of the fired ceramic unit is by means of 35 a fluid and preferably a liquid. The use of a fluid or liquid for transmitting heat units, has in many instances peculiar advantages over the use of a plastically applied but unfired stone.

40 In the drawing:
I have shown a water cooling unit embodying my invention in vertical section.

In illustrating the present invention I have shown the same as embodied in a typical 45 water cooler of the type utilizing mechanical refrigeration, but it will be understood that the invention can be equally well embodied in practically any type of refrigerating unit desired.

50 In the embodiment shown in the drawing

the cooling unit may be designated 1 and is preferably cylindrical and hollow in shape. This cooling unit is preferably formed of a fired ceramic material and it will be obvious that it may be formed in many varying 55 shapes. The bottom of the cylindrical hollow cooling unit is preferably formed with an aperture, as at 2, which is large enough for the insertion of a suitable refrigerating unit which may be generally designated 3.

The inner wall of the hollow fired ceramic unit 1 is preferably formed with an inwardly projecting portion 4 which may be of any shape and size desired, and in the illustration is large enough to receive the refrigerating 65 member 3, and at the same time furnish suitable clearance around the same. This inwardly projecting portion 4 may be suitably formed at the top thereof, as at 5, to receive the upper end of the refrigerating member 70 3 and also to provide a space for the reception of a fluid or liquid, as will be later described.

The refrigerating member 3 is preferably of the flooded system type, that is, it is adapted to receive and maintain a given level of refrigerant therein, but it may be understood that it may be of any shape desired and may be, if necessary, provided with a suitable float valve, or it may be in the form of a 80 suitable direct expansion device.

Whatever the form of the refrigerating means, it is preferably of such shape that it may be easily inserted through the aperture 2, the aperture 2 being adapted to be closed 85 by a suitable plug 6. The aperture 2 may be provided with suitable threads adapted to complementally fit with suitable threads on the plug 6, and such plug 6 may be designed to receive suitable conduits 7 and 8 for conducting the refrigerant to and from the unit 3. The function of the plug 6 of course is to seal the hollow unit 1 whereby brine or any other suitable liquid, preferably of the non-freezing type, may be inserted into the 95 hollow fired ceramic cooling unit, to serve as a medium for transmitting the heat units between the contents of the unit 1 and the member 3. Such brine may be a saturated solution of calcium chloride, magnesium 100

chloride, alcohol and water, or water and glycerine, or any other liquid that will stand extremely low temperatures without freezing. Furthermore, such liquid, or fluid, as the case may be, in addition to readily adapting itself to all conditions of expansion and contraction, also serves as a good holdover, and for this reason the member 3 is preferably completely spaced in the wall or walls of the unit 1 whereby said liquid or fluid will fill up such space.

The mechanism for controlling and circulating the refrigerant is diagrammatically shown, and as such comprises the power unit 9, a condenser 10, and a capillary coil 11 for controlling the flow of refrigerant 2, and maintaining the level of the refrigerant in the member 3.

It will be understood that the cooling unit 1 may be of any desired shape and may be designed to receive water, or for the freezing of water, or for the storage of food stuffs or the like. It will further be understood that the sealing and filling of this hollow fired ceramic unit may be accomplished in various manners, and that the aperture for receiving the refrigerating means and the liquid or fluid may be also located at different positions, or in other words, the refrigerating unit may be inserted at a point from or positioned at the side or even at the top, and if desired, the liquid or fluid may be inserted at another point spaced from the point of insertion or location of the refrigerating member. The refrigerating member 3 is preferably insertable and removable as a unit, but it will be understood that if desired, the conduits may be permanently formed in or carried by the refrigerating cabinet or supporting structure, and detachably connected to the refrigerating member.

It will thus be seen that I have provided a cooling unit which may be molded of ceramic material and fired to form a unit of very pleasing appearance, and which unit, whether hollow or combined with other cooperating means, is adapted to receive a refrigerating coil or the like, and also to receive and contain a liquid or fluid heat conducting medium. The heat transmission between the refrigerating means and the contents of the cooling unit is very efficient, and in view of the use of the liquid or fluid, the entire unit has a large holdover capacity. Furthermore, it will be seen that the entire unit and system is very simple and inexpensive and easily assembled. The fired ceramic cooling unit presents a very sanitary surface, one that is very easily cleaned, and presents a pleasing appearance, and this fired ceramic material also not only is a good conductor of heat but is also a good holdover, and this combined with the liquid or fluid conducting medium aids materially in the running efficiency of the refrigerating apparatus.

What I claim is:

1. Refrigerating apparatus, comprising in combination a cooling unit formed of fired ceramic material, refrigerant receiving and conducting means forming a part of an automatic refrigerating system, located in proximity to an isolated portion of said wall or walls of fired ceramic material, and means in the form of a fluid serving as a heat conductor between said refrigerant receiving and conducting means and all the effective walls of said fired ceramic material.

2. A refrigerating apparatus comprising a cooling unit formed of a one piece hollow shell of fired ceramic material, a refrigerant receiving and conducting member positioned within but spaced from the inner wall of said shell, and a body of non-freezing liquid contained within the shell and acting as a heat transmitting medium between the refrigerant receiving and conducting member and the walls of the shell.

3. Refrigerating apparatus comprising, a cooling unit having its exposed surface formed of a fired ceramic material, a body of non-freezing liquid positioned adjacent said exposed surface of fired ceramic material, and refrigerant conducting means forming a unit in a refrigerating system positioned and immersed within said body of liquid, but spaced from said fired ceramic material.

4. Refrigerating apparatus comprising, a cooling unit formed of a hollow fired ceramic shell, an opening formed therein for the insertion of a refrigerant receiving and evaporating member, a body of liquid surrounding said member, and a plug for said opening adapted to retain said liquid within said hollow shell.

5. A refrigerating apparatus, comprising a cooling unit formed of a fired ceramic material, said material or stone being of a consistency to act as a good conductor of heat, and also to act as a holdover, a body of liquid having relatively high heat conducting and holdover properties adjacent said fired ceramic material, and a refrigerating member forming a unit in a refrigerating system for receiving and circulating refrigerant, immersed in said liquid but spaced from said ceramic material.

6. A refrigerating apparatus comprising, a cooling unit formed of a hollow shell of stone, a refrigerant receiving and conducting member positioned at an isolated point within said shell, and a body of non-freezing liquid having relatively high heat conducting properties contained within the shell and acting as a heat transmitting medium between the refrigerant receiving and conducting medium and all the effective walls of the shell.

In testimony whereof I affix my signature.
LLOYD G. COPEMAN.
